The ornamental design for an electric foldable device of a rearview mirror for automobiles, as shown and described.

DESCRIPTION

FIG. 1 is a front view of an electric foldable device of a rearview mirror for automobiles, according to the present invention.

FIG. 2 is a rear view of the electric foldable device of a rearview mirror for automobiles of FIG. 1;

FIG. 3 is a top view of the electric foldable device of a rearview mirror for automobiles of FIG. 1

FIG. 4 is a bottom view of the electric foldable device of a rearview mirror for automobiles of FIG. 1;

FIG. 5 is a left view of the electric foldable device of a rearview mirror for automobiles of FIG. 1;

FIG. 6 is a right view of the electric foldable device of a rearview mirror for automobiles of FIG. 1; and,

FIG. 7 is a perspective view of the electric foldable device of a rearview mirror for automobiles of FIG. 1.

The broken lines where present illustrate portions of the electric foldable device of rearview mirror for automobiles that form no part of the claimed design.

1 Claim, 7 Drawing Sheets
